UNITED STATES PATENT OFFICE.

HAROLD TAYLOR ROBINSON, OF MARKET DRAYTON, ENGLAND, ASSIGNOR TO JOHN DAVISON INC., OF NEW YORK, N. Y., A CORPORATION OF NEW YORK.

DESIGN FOR A COVERED DISH OR SIMILAR ARTICLE.

Application filed April 9, 1929. Serial No. 30,813. Term of patent 14 years.

To all whom it may concern:

Be it known that I, HAROLD TAYLOR ROBINSON, a subject of the King of Great Britain, residing at Mucclestone Hall, Market Drayton, county of Shropshire, England, have invented a new, original, and ornamental Design for a Covered Dish or Similar Article, of which the following is a specification, reference being had to the accompanying drawing, forming part thereof.

I claim:

The ornamental design for a covered dish or similar article as shown.

HAROLD TAYLOR ROBINSON.
